Primary Examiner — Carol P Rademaker(74) *Attorney, Agent, or Firm* — Dorsey & Whitney LLP;
Kenneth E. Levitt, Esq.(57) **CLAIM**

The ornamental design for a combined container and bottle, as shown and described.

DESCRIPTION

FIG. 1 is a top, front, left side perspective view of a combined container and bottle showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.

The broken lines shown in the drawing views are included for the purpose of showing environmental structure that forms no part of the claimed design.

1 Claim, 6 Drawing Sheets---
